UNITED STATES PATENT OFFICE.

GEORGE S. LONG, OF HARTFORD, CONNECTICUT.

PULLEY.

SPECIFICATION forming part of Letters Patent No. 274,349, dated March 20, 1883.

Application filed March 11, 1882. (No model.)

To all whom it may concern:

Be it known that I, GEORGE S. LONG, of Hartford, in the county of Hartford and State of Connecticut, have invented certain new and useful Improvements relating to the Construction of Pulleys, of which the following is a specification.

My invention may be employed in the manufacture of pulleys of a great diversity of sizes and forms; but it is more especially important in making large pulleys of considerable width for use on the line-shafting and other shafting of manufactories. I will describe it as applied to the manufacture of such pulleys. The iron pulleys ordinarily employed for such situations add greatly to the weight of the shafting and to the friction and wear. I make pulleys of equal and greater efficiency with less weight. I employ paper as the material for the periphery. The hub and arms may be of cast-iron or other suitable material, the ends of the arms being provided with broad bearing-surfaces, on which a specially-prepared rim of paper is applied and secured by riveting or other suitable means. I can make my pulley in two pieces and realize the facility of application and removal on any part of a shaft, due to such construction. The frictional qualities of my paper surface very considerably excel that of iron. I can give any required degree of roundness or convexity to the periphery. I can run my improved pulleys with safety at a very high velocity by reason of the strength and lightness of its periphery.

The accompanying drawings form a part of this specification, and represent what I consider the best means of carrying out the invention.

Figure 1 is a side view of a pulley, partly in section, with the embracing-clamps which are employed to temporarily confine the rim. Fig. 2 is an edge view, and Fig. 3 a corresponding central section. In Fig. 2 the clamping-band is omitted. Figs. 4, 4^a, and 4^b show my paper rim in three successive stages of the manufacture. The drawings are cross-sections through the rim and through the adjacent portions of the rolls employed to compress and shape the paper-pulp for the rim. Fig. 5 is an end view of the split arms where the two parts of the center or spider are joined. Fig. 6 is an end view of one of the ordinary arms. Fig. 7 is a corresponding view of the end of one of the arms on

which the abutting ends of the rim are brought together and secured. Fig. 8 represents a modification. It is a central longitudinal section. 55

Similar letters of reference indicate corresponding parts in all the figures.

A is a hub, of cast-iron or other suitable material, formed in two parts matched together and strongly bolted, and provided with a key-seat for securing on a shaft. (Not represented.)

A' A', &c., are arms, which may be curved to any desired degree, but which I prefer, for general purposes, shall be made exactly straight.

A² A² are broad flanges or faces formed at the outer ends of the arms to receive my paper rim.

The invention may be carried out with some success by making the bearing-surfaces A² simply rectangular; but I prefer to give them the form of a Greek cross. The rivets C are applied in both branches of the cross, as represented.

B is the rim. It is of paper, or of compacted paper-pulp analogous to paper. Its inner surface is exactly cylindrical. Its outer surface is swelled to exactly the degree required to retain the belting properly while running.

The material for the rim is prepared in the same manner as for paper, with a proper amount of sizing to give great hardness and tenacity, with the capacity for resisting moisture. It is reduced to form by passing through successive pairs of rollers, care being taken to cause the first rolling while the pulp is wet and highly plastic to reduce the material to the form required, excepting that it is a little too thick. The subsequent rollings exclude more water and condense the fibrous mass more and more without changing its form, except to reduce its thickness. When completed the edges are trimmed by a revolving knife and the ends cut off. Then the whole is curved by bending it around the previously-prepared skeleton of the wheel and confining it in place until set by properly-formed clamps operated by screws or otherwise. The abutting ends are not straight, but are formed the one with a recess, b, and the other with a corresponding tongue, b', as shown clearly in Fig. 2. These, being properly matched together, present a smooth surface on the exterior and strongly lock each

other against lateral displacement. The moisture having been expressed from the material by the successive rollings, its hardness approximates to iron. The clamp should be perfectly circular, but its width should be much less than the rim B of the pulley. Mounting the partially-completed pulley by its center on a suitable mandrel, the several points in its periphery are bored by a proper drilling-machine and the outer face slightly counterbored or countersunk. The holes are bored through both the hard-paper rim B and the broad flanges A². Soft-iron rivets C are finally applied from the inside outward, and are properly held and riveted. The spread due to the riveting should exactly fill the countersink and leave the exterior surface flush. For narrow pulleys the riveting on each edge is sufficient. For wide pulleys the clamp is removed and another line of rivets put in along the central space previously covered by the clamp.

It will be observed that there are two lines of rivets at the junctions of the hard-paper periphery.

25 My wheel is lighter with a given width and strength than any before known to me. It will endure all ordinary and extraordinary usage to which it is liable to be subjected. It allows the periphery to be swelled to retain 30 the belt, and the edges to be sheared and smoothed with great perfection.

Modifications may be made in the forms and proportions of the details. The hard-paper rim may be shaped by molding or various other means, if preferred, instead of rolling. I propose, in cases where the expense will be warranted, to build up the hard-paper rim by successive layers of thinner paper material. This may be accomplished by winding the web of 40 paper as it is received from a Fourdrinier or other paper-machine, and subsequently passing it through rolls a number of times with a properly-severe pressure. In such case the paper-stock is accumulated evenly, or nearly 45 so, with the fibers lying more uniformly than when applied in a mass of pulp; but for ordinary pulleys such refinement is not necessary. The entire wheel may be painted or otherwise coated to improve its appearance and defend 50 its iron portion against corrosion and other injuries. The paper will serve well either with or without painting. Where it is desired to make the pulley in two halves the entire periphery may be made in one piece, with its 55 ends abutting squarely together; but in all cases I prefer that the skeleton or center shall

be made with the opposite arms exactly alike, so as to balance.

My pulley may be made in sections of small diameter for spinning-frames, mules, &c., so 60 as to form in effect one continuous cylinder having no abutting ends; or I can make my rims for such small pulleys or for any pulleys in one continuous cylinder. Such may be made, like a paper barrel, smaller or larger 65 around, and of any length. I can use such to replace the long metallic drums or cylinders now used in silk, cotton, and woolen mills. This form is shown in Fig. 8.

My improved pulley may have spokes or 70 arms of half-round wrought-iron or rolled steel, each with a curved arm from its outer extremity, extending the whole length of the arc from it to the next, and matching in a proper recess in its neighbor, thus re-enforcing the paper in a continuous line around the periphery. When the pulley is so constructed the hub may 75 be united to the spokes or arms by casting it to them.

The skeleton or framing of my pulley may 80 be made in two halves, still retaining this general construction of spokes, in which case the pulley may be removed from or placed on a line of shafting by removing the fastening-bolts and springing it open, so that the two 85 halves separate enough to allow the shaft to pass into or out of the hub.

I am aware that it is not broadly new with me to construct a pulley the periphery of which is partially or wholly made of paper with a 90 rounded outer surface; nor is it broadly new with me to employ a split spider, as these features have been before employed in other constructions to perform their separate functions.

What I do claim is—

95 In a belt-pulley, the combination of the frame or spider, formed in sections, and composed of the hub A and arms A', having curved bearings A², and means for securing said sections firmly together, with the rim B, made of paper, having its outer surface convex in transverse section, and having its adjacent ends formed with tongue b and recess b', as and for the purposes set forth.

In testimony whereof I have hereunto set my 105 hand, at New York city, this 7th day of October, 1881, in the presence of two subscribing witnesses.

GEORGE SAM'L. LONG.
